AUGUST KAZENMAIER AND EUGEN BAUER, OF STUTTGART, GERMANY, ASSIGNORS TO
THE FIRM OF ROBERT BOSCH, OF STUTTGART, GERMANY.

STARTING APPARATUS FOR INTERNAL-COMBUSTION ENGINES.

1,275,940.

Specification of Letters Patent. Patented Aug. 13, 1918.

Application filed March 6, 1914. Serial No. 822,877.

To all whom it may concern:

Be it known that we, AUGUST KAZENMAIER and EUGEN BAUER, both subjects of the Empire of Germany, and residents of Stuttgart, Germany, have invented certain new and useful Improvements in Starting Apparatus for Internal-Combustion Engines; and we do hereby declare the following to be a full, clear, and exact description of the invention, such as will enable others skilled in the art to which it appertains to make and use the same.

In starting internal-combustion engines from rest, not only has the inertia of the moving parts and their friction to be overcome, but also the compression in the cylinders, so that starting motors which are mechanically connected to the engine for this purpose must have comparatively large power output, and if the starting motor is of the electric type, the battery or other source of current supply must be of sufficient capacity to supply the large demand at starting. These demands are sometimes increased during starting by abnormal frictional resistance in the bearings, or because of connection of the engine to the driving shaft of the automobile, motor-boat, or other load with which the engine is associated. Hence, it has been proposed heretofore to preliminarily rotate an element normally disconnected from the engine when the engine is at rest, and then, when sufficient energy of rotation has been stored up, to mechanically connect the rotating element to the engine to start it. However, in such systems, the source of current supply remains connected to the electric motor and the rotating element remains clutched to the engine after the engine has been turned over, so that the starting motor then acts directly on the engine. If, in this case, an undue amount of the stored energy is absorbed before the engine has established its normal cycle of operations, the electric motor drives the engine directly through the connecting parts, and its output may be increased to an undesir-

able value as before. To avoid this exigency, the motor could be disconnected from the driving element as soon as the driving element is clutched to the engine, but the series motor usually used for starting purposes of this kind would then race to a dangerous speed, if the source of current supply remained connected to the motor. This could be avoided by also disconnecting the source of current supply at this time. However, the variety of operations which must be performed in a necessarily definite order and at the proper moments imposes severe requirements on the operator and at just the time when close attention must be paid to other matters. Furthermore, failure in any respect may overload the system, or, in other ways, render the system ineffective or dangerous.

In accordance with our invention, the starting motor is of the series type and is permanently coupled to a rotatable element which is designed to be connected with and disconnected from the engine. After the rotatable element is driven by the motor to that speed at which sufficient kinetic energy is stored up in the rotating parts to speed up the engine from rest until its normal cycle of operations is reliably established, the motor is disconnected automatically from the source of current supply, or the supply of current thereto is reduced, and the rotatable element is then clutched to the engine. The rotatable element may be clutched to the engine either automatically or by hand, but in either case the clutch is locked in an open position until the current supply to the motor has been reduced to zero or to a comparatively small value, as the case may be. When the engine has attained a predetermined speed of operation, it is disconnected automatically from the rotatable element and is then ready to be clutched to the driving shaft for propelling the vehicle or other load. In the case where the rotatable element is automatically clutched to the engine, the operator is only required to close a start-

ing switch, whereupon the rotatable element is speeded up, the supply of current to the motor is reduced at the proper time, the rotatable element is clutched to the engine and then disconnected therefrom when the engine cycle is reliably established. In the case where the rotatable element is clutched to the engine by hand, the proper sequence of operations is compelled, but the subsequent operation of manually clutching in the engine is necessitated.

If desired, the motor may also be used as a generator to supply ignition currents for the spark plugs of the engine, and after the engine has been started it may be used also for lighting purposes or for charging a battery, in the well known way.

In the accompanying drawings, illustrating our invention diagrammatically,

20 Figure 1 shows the preferred embodiment wherein the entire starting operation is automatic, and requires only that the operator depress the starting switch;

25 Fig. 2 shows a modification wherein the starting motor and the clutch between the rotatable element and the engine are compelled by a hand lever to be connected in the proper sequence;

30 Fig. 3 shows an arrangement similar to that of Fig. 2, excepting that some of the operations are controlled by springs; and

35 Figs. 4 and 5 particularly show specific forms of the automatic switch for reducing the current supply to the starting motor at the proper moment.

Referring particularly to Fig. 1, the source of electric current comprising the battery *a* is electrically connected to the magnet coil *b* of the automatic cutout *c*, 40 from which the current passes by way of the armature and the field winding of the series electric motor *d* to the magnet winding *e* of the clutch *f* when the contacts *m* and *n* of the automatic cutout are engaged. The 45 other end of the magnet winding *e* is connected to the other terminal of the battery through the starting resistance *h* or the short circuiting contacts 8, 9, as the case may be. The starting switch *g* is adapted to be operated 50 by foot pressure and is electrically connected in parallel with the motor circuit, so that the winding *b* can be energized when the contacts *m*, *n* are apart to thereby pull the armature *l* up against the pressure of spring *k* until these contacts are engaged. The starting resistance *h* for the motor is 55 in the circuit of the motor when the motor is speeding up, but is short circuited by the contacts 8, 9 when the current in the magnet coil *i* increases to such a value that the attraction of the armature 7 of the relay is sufficient to overcome the spring 10.

The spring *k* holds the armature *l* depressed when the magnet winding *b* is not

energized and thereby holds the movable contact *m* away from the stationary contact *n*. These contacts can be engaged by raising the armature *l* by hand, whereby the magnet winding is energized and holds the contacts in engagement so that current is supplied from the battery *a* to the motor *d*.

The contacts *m*, *n* can also be engaged by depressing the button *o* of the starting switch *g*, whereby the spring pressed contact *p* is brought into engagement with the sta-

75 tionary contact *q* to thereby close a circuit including the magnet winding *b*. The starting switch *g* is constructed in such manner that it produces but a momentary closing

at the contacts *p*, *q*, whereby the subsequent 80 automatic interruption of the motor current, as will be hereinafter described, can

not be prevented. When the button *o* is de- 85 pressed against spring *r*, the plate *s* first acts against a spring pressed ball *t'* and the

spring *u*, which pushes the plate *s* outwardly 90 is stressed until the plate *s* presses the ball *t'* out of the way and snaps below it. The

plate *s* then strikes a second ball *t* and mo- 95 mentarily brings the contacts *p*, *q* into en-

gagement, whereupon the spring *u* is again stressed until the ball *t* is pushed out of the

way. The plate *s* then snaps below this ball 100 and the contact *p* is spring pressed upwardly until it interrupts this shunt path. Thus

the button *o* may be held depressed without closing this shunt path longer than is re- 105 quired to bring the contacts *m*, *n* into en-

gagement.

The winding of the starting relay *i* is 100 shunted across the terminals of the motor *d*, and serves to short circuit and thereby cut out the starting resistance *h* after the motor has started to run. As the motor is speed- 105 ing up, the voltage across its terminals rises, and the current in the winding of relay *i* in- 110 creases until the attraction of the armature 7 is sufficient to overcome the spring 10. The contacts 8 and 9 are then engaged and the starting resistance *h* thereby short cir- 115 cuited. The motor then receives full voltage and continues to increase its speed.

The clutch member *v* is permanently connected to the motor shaft *x* by means of a feather and groove connection, and is shift- 120 able longitudinally along the shaft so as to be moved from a position of disengagement with the co-operative clutch member 5 to a position of driving engagement therewith. The clutch member *v* carries an armature *y* which is acted upon by the electromagnet *z*, and is attracted thereby to a position of dis- 125 engagement with the clutch member 5 when the electromagnet is energized by current flowing in the winding *e* to such a degree as to overcome the stress of the opposing spring 1. The spring 1 is fastened at one end to a flanged ring 3. Ball bearings are inter-

posed between the ring 3 and the crowned surface 4 of the clutch member v . The opposite surface of the clutch member v is also crowned so as to form a cone coupling with 5 the coöperative member 5, the latter member being fastened on an independent shaft carrying a gear to drive the crank shaft w of the internal combustion engine through the intermediacy of an overrunning clutch 11.

10 The arrangement is such that as long as current flows through the winding e , the clutch member v is held against the pressure of the spring 1 out of engagement with the coöperative clutch member 5, but as soon as 15 the motor current is interrupted, the spring 1 under stress forces the clutch member v into driving engagement with the member 5 and thereby mechanically connects the crank shaft w of the engine to the motor shaft x .

20 The operation of the arrangement previously described is as follows: When the internal combustion engine is to be started from rest to establish its normal cycle of operations, the chauffeur or other operator 25 engages the contacts m , n either by manually pulling up the armature l or by depressing the button o of the starting switch. The starting current then flowing through the starting motor d speeds up this motor and 30 when it attains a predetermined speed, say about six hundred revolutions per minute, the starting resistance h is automatically cut out so that the speed of the motor increases rapidly above this value. At another predetermined speed, for instance three thousand revolutions per minute, the value of 35 the starting current becomes so small that the spring k disengages the contacts m , n and thereby interrupts the current flow from 40 the battery a to the starting motor d . Simultaneously therewith, the winding e of the electromagnet z becomes deénergized and the spring 1 closes the coupling v , 5. The energy stored in the rotating element v , 45 together with the energy stored in its associated parts, is such that the engine is rapidly brought up to that speed at which its cycle of operations is reliably established. The engine then further increases in speed 50 under its own power and at a higher value of speed the overrunning clutch 11 automatically disconnects the crank shaft w of the engine from the shaft x of the starting motor, whereupon the entire starting system 55 comes to a standstill. If, for any reason, the engine does not start, the entire system comes to rest without the possibility of any damage whatsoever, inasmuch as the starting current has been interrupted, even 60 though the starting switch g is held depressed. When the engine is to be started again, the clutch v , 5 is disengaged as a result of the current passed through the winding e .

In the modification shown in Fig. 2, the 65 first part of the movement of a hand lever closes the circuit from the source of current supply to the starting motor, but is locked in position from further movement until the starting current decreases to a value at 70 which the circuit is interrupted, whereupon the lever may then be further moved to close the clutch between the rotating element and the internal combustion engine to start the engine from rest. The armature l of the 75 circuit breaker c carries a movable contact m into and out of engagement with a stationary contact n , and is spring pressed against attraction by the electromagnet by the bow spring k . The starting lever 13 80 carries a rail 14 and can be moved between the positions O and I shown in broken lines. The rail 14 is connected by the links 16 and 17 to the rod 18 which carries an arm 19 for shifting the clutch member 5 into and 85 out of engagement with the coöperative clutch member v . The clutch member v is fastened on the shaft of the starting motor d while the clutch member 5 is shiftable along its shaft by reason of a feather and 90 groove connection therewith. The rail 14 carries a spring lever 20 having a knob 21 on its end, and the rail also carries a lug 22. A guide 23 separate from the rail 14, is provided with inclined outer surfaces. A bent 95 lever 24 is pivoted to the piece 25 and is pressed by the spring 26 against an abutment on the piece 25. The lever 24 has a projection lying within the path of movement of the armature l , and also has its end 100 in the line of movement of the stop 22 when the lever 24 is held in raised position by the spring 26.

The operation of the arrangement shown in Fig. 2 is as follows: In order to start 105 the engine from rest, the starting lever 13 is moved from its 0 position to shift the rail 14 toward the right. During this movement the knob 21 slides along the surface 27 of guide 23 and through the intermediacy of 110 the projection 12 raises the armature l until the contact m is brought into engagement with the contact n , whereupon the starting current flows from the battery a through the winding b of the electromagnet c and thence through the series motor d back to the battery. At the same time the lever 24 is raised by its spring 26 so that its end projection prevents further longitudinal movement of 115 the projection 22 beyond it. The motor d speeds up until the predetermined speed at which the required energy is stored in the rotating parts is reached. The arrangement is such that when this predetermined speed is reached, the starting current has 120 become so small in value that the attraction of the armature l is overcome by the stress of the spring k . The armature l is there-

upon forced down, and in its movement pushes the end of the lever 24 against the stress of spring 26 out of the path of the lug 22. Up to this time, the starting lever 13 was prevented from further movement so that the clutch v , 5 was compelled to be open, but after this time the starting lever 13 may be moved to its position I to close the clutch v , 5 and thereby apply the energy stored in the rotating parts on the crank shaft w of the engine through the intermediacy of the gears 6 and the overrunning clutch 11. During this latter portion of the movement of rail 14, the knob 21 is raised by the inclined surface 28 to such a point that it thereafter snaps under the guide 23 so that when the rail 14 is being moved back to its 0 position the knob 21 does not lift the armature 7. When the rail 14 has reached its 0 position, the knob 21 snaps into its normal position so as to slide along the surface 27 of the guide 23 when the rail is again moved to the right. The armature 7 holds the lever 24 depressed until the armature is again raised by the knob 21.

In the modification shown in Fig. 3, the clutch between the rotatable element and the engine is closed automatically after the starting current to the motor is interrupted without any subsequent movement of the starting lever, and furthermore the clutch is opened automatically to disconnect the starting apparatus from the engine and the lever is automatically returned to its starting position, when the starting lever is released after the engine has come up to speed. The clutch member v is fastened on the shaft x of the armature of the series motor d , while the coöperative clutch member 5 is slidable thereon, in constant driving connection therewith. The abutment 22 is carried on a rod 29 slidable longitudinally of the rail 14. The outer end of the rod 29 is provided with an end projection 31 in line with the shaft of the clutch member 5, and the spring 30, when compressed, tends to move the rod 29 to the right relatively to the rail 14. The tension spring 32 tends to return the rail 14 and the starting lever 13 to their 0 position when the starting lever 13 is released, and the compression spring 33 tends to separate the clutch members v and 5 from driving engagement.

The operation of the arrangement shown in Fig. 3 is as follows: To start the engine from rest, the starting lever is moved from its 0 position to the position indicated by I, the rail 14 being thereby moved to the right against the stress of spring 32. During this movement of the rail 14, the armature 7 is raised until the contacts m , n engage each other and thereby close the circuit from the battery through the winding b and the starting motor d . The rod 29 is moved to the

right by the compression spring 30 until 65 the abutment 22 carried by the rod 29 is prevented from further movement by the end of the spring pressed pivoted lever 24. As soon as the starting current has fallen sufficiently, the spring z overcomes the attraction on the armature 7 and thereby depresses the armature and pushes the end of the lever 24 out of the path of further movement of the stop 22, whereupon the compression spring 30 forces the end 31 of the rod 75 against the shaft of the clutch member 5. The clutch is closed in this way against the stress of the compression spring 33, and the energy of rotation stored in the rotating element is applied through the gears 6 and 80 the overrunning clutch 11 to the crank shaft w to start the engine from rest. When the engine is running under its own power, the starting lever 13 is released, and the clutch members v and 5 are disconnected by the 85 stressed spring 33, while the rail 14, with the rod 29 and also the starting lever 13, are brought to their 0 position by the stressed spring 32. The remaining features of operation of this modification will be apparent 90 from the foregoing description of the arrangement shown in Fig. 2.

In Fig. 4, the electrical circuit between the battery a and the series motor d is automatically interrupted by a centrifugal 95 switch when the motor attains a predetermined speed, at which the energy stored in the rotating element is sufficient to start the engine from rest. The switch 35 carrying the spring pulled blade contacts 41 coöperative with the contacts 36, 37, is attached to a tension spring 38 tending to engage the coöperative contacts, and the switch is also provided with a housing 39 in which the sliding arm 40 of the centrifugal switch 100 moves freely in such manner that it does not separate the coöperative circuit contacts until the series motor d attains a predetermined speed. The construction and operation of the clutch mechanism f between the 105 rotatable element and the engine is arranged and connected as in Fig. 1, so that when the starting current is interrupted at the coöperative circuit contacts the coupling is 110 automatically closed to start the engine from rest. In order to utilize the gradual movement of the longitudinal moving element of the centrifugal switch as the speed of the motor shaft gradually increases, the blade contacts 41 are spring seated. The starting lever 42 is held by the tension spring 43 in the position in which it holds the circuit contacts out of engagement, but by moving the starting lever into the dotted position, the spring 38 pulls the switch 35 into its operative position and the circuit is closed to start the motor d . The hand lever is held 115 in this starting position until after the time 120 125

that the circuit is interrupted as a result of the movement produced by the centrifugal switch. When the starting lever is released, it is retracted into its normal position by 5 the spring 43 against the stress of spring 38.

Fig. 5 shows a modification in which the automatic circuit breaker or cutout is provided with two windings *b* and 44 in electrical parallel with each other. A starting 10 switch *g*, like that of Fig. 1, is connected in the circuit of the winding 44 and serves for bringing the contacts *m*, *n* into engagement, while the winding *b* is in series with the motor *d* through these contacts and 15 serves to hold the armature *l* in its raised position until the current therein falls to a predetermined low value. In this modification the winding *e* of the electromagnet operative upon the clutch mechanism *f* is not 20 connected in the main circuit to the motor *d*, but is shunted there around. If desired, a high resistance 55 can be connected across the contacts *m*, *n*, so that the starting current is not interrupted when the circuit 25 breaker opens, but is reduced to a small value sufficient to prevent overloading the battery or the motor. The resistance 55 is so proportioned that the current passing through the system when the contacts *m* and *n* are out 30 of engagement is not sufficient to permit the clutch member *v* to be moved from engagement with the clutch member 5.

The specific embodiments shown in Figs. 2 and 3 herein form the subject matter of our 35 divisional application Serial No. 76,205, filed February 4, 1916.

Having thus described our invention, what we claim is:

1. In apparatus for starting internal combustion engines from rest, a source of electric current, a rotatable element designed to be connected with and disconnected from the engine, an electric starting motor for driving the rotatable element, an electromagnetically operated clutch which, when energized, holds the rotatable element out of connection with the engine, and which, when the motor reaches a speed appropriate for starting the engine, connects the rotatable 40 element with the engine, and an electromagnetic switch having contacts in the circuit of the motor and the electromagnetically operated clutch and having an energizing winding calibrated to open said contacts 45 when the current to the motor reaches a predetermined low value corresponding to the speed appropriate for starting the engine.

2. In apparatus for starting internal combustion engines from rest, a source of electric current, a rotatable element designed to be connected with and disconnected from the engine, an electric starting motor for driving the rotatable element, an electro-

magnetically operated clutch which, when energized, holds the rotatable element out of connection with the engine and which, when the motor reaches a speed appropriate for starting the engine, connects the rotatable element with the engine, an electromagnetic switch having contacts in the circuit of the motor and the electromagnetically operated clutch and having an energizing winding calibrated to open said contacts when the current to the motor reaches a predetermined low value corresponding to the speed appropriate for starting the engine, and manually-operative means for initially connecting the energizing winding of the electromagnetic switch to the source of current to close said contacts. 75

3. In apparatus for starting internal combustion engines from rest, a source of electric current, a rotatable element designed to be connected with and disconnected from the engine, an electric starting motor for driving the rotatable element, automatic means for suddenly decreasing the current from the source to the motor when the rotatable element has attained a predetermined speed, means for connecting the rotating element to the engine when such decrease of current has occurred, and automatic means for disconnecting the rotating element and the engine, substantially as described. 90

4. In apparatus for starting internal combustion engines from rest, a source of electric current, a rotatable element designed to be connected with and disconnected from the engine, an electric starting motor for preliminarily driving the rotatable element, a circuit breaker having an energizing winding and contacts in the circuit of the motor, a manually operated switch and connections arranged to momentarily energize the winding of the circuit breaker to engage said contacts in order to complete the circuit of the motor, and means for connecting the rotatable element to the engine to start it, substantially as described. 100

5. In apparatus for starting internal combustion engines from rest, a source of electric current, an electric starting motor, means for connecting the motor to the engine to start it, and a circuit breaker having an energizing winding and contacts connected in the electrical circuit of the motor armature and having manually-operated means for engaging said contacts to complete the circuit to the motor and to energize said winding, the energizing winding being calibrated to release the circuit breaker and thereby open the circuit to the motor armature when the motor attains a predetermined speed appropriate for starting the engine, 115 substantially as described. 120

6. In apparatus for starting internal combustion engines from rest, a source of elec-

trical current, an electric starting motor, means for connecting the motor to the engine to start it, electrically controlled contacts in the circuit of the motor, and a starting switch for effecting the engagement of said contacts to close the circuit to the motor, said starting switch comprising two contacts spring-pressed apart and a contact closing member adapted to first engage the contacts and in the same stroke to immediately

thereafter permit the separation of said contacts, substantially as described.

In testimony whereof we affix our signatures, in presence of two witnesses.
